CLAIM

The ornamental design for foldable easel, as shown and described.

DESCRIPTION

FIG. 1 is a front elevational view of foldable easel embodying the design of the present invention, and shown in an unfolded condition thereof;

FIG. 2 is a front elevational view of the subject design, as seen in a folded condition thereof;

FIG. 3 is a back elevational view of the subject design in the folded condition thereof;

FIG. 4 is a left side elevational view of the subject design, in the folded condition thereof;

FIG. 5 is a right side elevational view of the subject design, in the folded condition thereof;

FIG. 6 is a top elevational view of the subject design, in the folded condition thereof;

FIG. 7 is a bottom elevational view of the subject design, in the folded condition thereof; and,

FIG. 8 is a perspective view in folded condition; the broken lines are for environmental purposes only and form no part of the claimed design.
